UNITED STATES PATENT OFFICE.

CHARLES G. CURTIS, OF NEW YORK, N. Y., ASSIGNOR, BY MESNE ASSIGNMENTS, TO GENERAL ELECTRIC COMPANY, A CORPORATION OF NEW YORK.

ELASTIC-FLUID TURBINE.

No. 923,146.

Specification of Letters Patent.

Patented June 1, 1909.

Application filed June 30, 1908. Serial No. 163,713.

To all whom it may concern:

Be it known that I, CHARLES G. CURTIS, a citizen of the United States, residing in the borough of Manhattan, city of New York, State of New York, have invented a certain new and useful Improvement in Elastic-Fluid Turbines, of which the following is a description.

My improvement relates to compound elastic fluid turbines of the jet type. Its object is to produce simple and effective means for compounding the action of the elastic fluid jet upon a single annular set of movable vanes.

In carrying out the invention I arrange at different circumferential points opposite the annular set of movable vanes two or more sectional nozzles. These nozzles I prefer to be of the same general character described in my Patent No. 700744, each of these nozzles being composed of a number of complete nozzle sections having the same form and angle of delivery and brought close together at their discharge ends, so that the jets or streams from adjacent sections merge into a substantially single jet or stream at the points of discharge. Since these nozzles receive the jet of elastic fluid in succession, they are made successively larger to accommodate the increased volume. The two or more sectional nozzles, however, have the same angle of delivery, because they deliver the fluid jet to the same set of movable vanes. Opposed to each sectional nozzle except the last one of the series, and located on the opposite side of the wheel so as to receive from the vane spaces the elastic fluid delivered to such spaces by the nozzle on the other side of the wheel, is a sectional receiving hood made in the form of a reversed sectional nozzle, the sections having each a throat and an enlarged chamber or bowl for converting the residual velocity of the elastic fluid into pressure. The sections of the receiving hood are set at a greater angle than those of the delivery nozzle, and this angle is made greater in the two or more receiving hoods, so as to receive the elastic fluid at approximately the same angle at which it is discharged from the vane spaces. The angles of the receiving nozzles will depend somewhat upon the distribution of the work and can be best determined by experiment. Each sectional receiving hood is connected with the next succeeding sectional delivery

nozzle by a number of pipes or conduits each of which includes one or more sections of the hood and nozzle, and the first delivery nozzle has its sections divided between two or more supply chambers which are opened and closed by valves under the control of the governor. Opposite the last delivery nozzle of the series is the exhaust opening of the turbine leading to an atmospheric or vacuum exhaust, or, in the case of a stage expansion machine, to the delivery nozzle of the next stage of the turbine. By the employment of divided delivery nozzles and receiving hoods and divided connecting passages between the receiving hoods and the delivery nozzles, the jet of elastic fluid is made more effective in its action on the vanes, and, further than this, the cutting off of more or less sections of the first delivery nozzle by the governor results in cutting off corresponding portions of the succeeding nozzles.

The preferable arrangement of the apparatus is one in which the first delivery nozzle is an expansion nozzle producing a conversion of pressure into velocity which reduces the pressure down to or near that of the exhaust opposite the last delivery nozzle of the series so as to insure the effective flow of the elastic fluid. The elastic fluid jet will therefore be delivered by the first nozzle to the vane spaces with the full velocity for which the turbine or turbine unit is designed. Since this velocity will be only partially extracted by the single passage through the vane spaces, the fluid will be received by the first receiving hood with considerable residual velocity, which will be converted into pressure by the reversed sectional nozzle which forms that receiving hood. The fluid jet will be conveyed from the first receiving hood to the second sectional delivery nozzle by the several connecting pipes or conduits, and the second delivery nozzle will again convert the pressure into velocity, reducing the pressure at its discharge end to a point near the exhaust pressure, and will deliver the jet at the proper angle to the vane spaces. The second delivery nozzle will have the walls of its sections beyond the throats parallel or approximately so, since only a throat conversion of pressure into velocity will be required at this point. The second receiving hood will receive the elastic fluid at the proper angle and will convert the residual velocity into pressure, the elastic

fluid being conducted from this second receiving hood to the third delivery nozzle, and there the pressure will be converted into velocity by a throat action and delivered to 5 the vane spaces, from whence it will be discharged into the exhaust or into another receiving hood, to be conveyed to another delivery nozzle, and so on to the end of the series. The elastic fluid jet being given the 10 maximum or full velocity at each delivery nozzle, which can be produced by reducing the pressure to near that of the exhaust opposite the last delivery nozzle, the maximum work will be performed by each passage 15 of the elastic fluid through the vane spaces.

In the accompanying drawing, Figure 1 is a view largely in diagram illustrating an apparatus embodying the invention; Fig. 2 is a 20 sectional view more in detail illustrating the first delivery nozzle and the first receiving hood; and Fig. 3 is a view similar to Fig. 2 illustrating two delivery nozzles and two receiving hoods, a connecting conduit or pipe being employed for each section of the nozzles and hoods.

Referring particularly to Figs. 1 and 2, A is the annular set of movable vanes, which are mounted upon a wheel in the ordinary 30 manner and are caused to rotate in the direction shown by the arrow. These vanes are shown as symmetrical in form because the fluid jet is delivered alternately to the vanes on opposite sides, but it is evident that unsymmetrical vanes could be employed and the delivery nozzles placed all on the same side of the wheel. B is the first 35 delivery nozzle, made in the form of a sectional nozzle such as is described in my patent before referred to, having sections substantially alike in form and in angle of delivery and brought close together at their discharge ends. The discharge ends *a* of these sections have diverging walls. Each 40 section is provided with a throat *b* and with an enlarged bowl or chamber *c* anterior to the throat. Back of the bowl *c* are a number of supply chambers *C* (four of such 45 chambers being illustrated). These supply chambers connect with the steam chest *D* by openings which are closed by valves *E* under the control of the governor. The 50 sections of the delivery nozzle B have the proper angle to deliver the elastic fluid effectively to the vane spaces. Opposite the nozzle B on the other side of the wheel is the receiving hood *F*, which is composed of a reversed sectional nozzle having sections 55 substantially alike in form and in angle, and brought close together at their respective ends. Each of these sections has a receiving end *d*, a throat *e*, and an enlarged bowl or chamber *f*. The sections of the 60 receiving hood *F* convert the residual velocity into pressure, and the elastic fluid is 65

conducted from this hood by a number of conduits or pipes *G*, the number corresponding with the number of supply chambers *C*, so that the cutting off of any one of the supply chambers cuts off the corresponding 70 pipe *G* of the opposing receiving hood.

The receiving hood *F* is set sufficiently forward of the delivery nozzle *B* to compensate for the forward movement of the elastic fluid in passing through the vane spaces, and the 75 angle at which the sections of the receiving hood are set is greater than the angle of the sections of the delivery nozzle so as to correspond with the angle at which the elastic fluid is discharged from the vane spaces. 80

The four pipes *G* connect the divisions of the sectional receiving hood *F* with the divisions of a second sectional delivery nozzle *H*. This second delivery nozzle is larger than the first delivery nozzle to accommodate the increased volume of the fluid, this enlargement being produced by giving the second delivery nozzle a greater circumferential length, since the radial height of the vane spaces is the same. The sections of the second delivery 90 nozzle have the same angle as those of the first delivery nozzle, but these sections have discharging ends which are parallel or approximately so, since the conversion of pressure into velocity produced by a throat action is sufficient. Opposite the second delivery nozzle *H* is a second sectional receiving hood *I* similar to the sectional receiving hood *F* but of greater circumferential length and having sections set at a greater angle. The 95 divisions of the receiving hood *I* are connected by pipes *K* with the divisions of the third sectional delivery nozzle *L*, which is similar to the nozzle *H* but has a greater circumferential length. Opposite the delivery 100 nozzle *L* is the exhaust hood *M* leading to an atmospheric or vacuum exhaust or to the nozzle of another stage of the turbine if the turbine has more than one stage. 105

In Fig. 3 the form of the sections of the second delivery nozzle *H* and the second receiving hood *I* is shown, but in this figure each division of the delivery nozzles and receiving hoods is shown as having only one section. 110

What I claim is:

1. In an elastic fluid turbine, the combination with an annular set of movable vanes, of two or more delivery nozzles arranged to deliver the elastic fluid to the movable vanes at different circumferential points, each of such nozzles converting pressure into velocity and producing at its delivery end a pressure near that of the exhaust opposite the last delivery nozzle of the series, a receiving hood opposing each of said delivery nozzles except the last and made in the form of a reversed nozzle and converting the residual velocity of the elastic fluid into pressure, and 120 passages connecting the delivery nozzles and 125

receiving hoods in succession, whereby the elastic fluid will be passed through the set of movable vanes two or more times in succession and will perform the maximum work at each passage therethrough, substantially as set forth.

- 5 2. In an elastic fluid turbine, the combination with an annular set of movable vanes, of passages conducting the elastic fluid through the movable vane spaces two or more times in succession, such passages being divided at the points of delivery of the elastic fluid to the vanes forming a sectional nozzle, all of the nozzles at each point of delivery being of substantially the same angle of delivery each of such nozzles converting pressure into velocity and producing at its delivery end a pressure near that of the exhaust opposite the last delivery nozzle of the series.
- 10 3. In an elastic fluid turbine, the combination with an annular set of movable vanes, of passages conducting the elastic fluid through the movable vane spaces two or more times in succession, such passages being divided at the points where the elastic fluid is received from the vanes forming a reversed sectional nozzle, all of the nozzles at each point of delivery being of substantially the same angle of delivery, substantially as set forth.
- 15 4. In an elastic fluid turbine, the combination with an annular set of movable vanes, of passages conducting the elastic fluid through the movable vane spaces two or more times in succession, such passages being divided at the points where the elastic fluid is delivered to and received from the vanes forming a sectional nozzle and a reversed sectional nozzle, all of the nozzles at each point of delivery being of substantially the same angle of delivery, substantially as set forth.

- 20 5. In an elastic fluid turbine, the combination with an annular set of movable vanes, of two or more sectional delivery nozzles arranged to deliver the fluid to the movable vanes at different circumferential points, a sectional receiving hood made in the form of a reversed sectional nozzle opposing each sectional delivery nozzle, and two or more conduits each connecting one or more sections of each sectional receiving hood with one or more sections of the next sectional delivery nozzle, such sectional delivery nozzles and sectional receiving hoods being connected thereby in succession, substantially as set forth.
- 25 6. In an elastic fluid turbine, the combination with an annular set of movable vanes, of passages conducting the elastic fluid through the movable vane spaces two or more times in succession, such passages being divided at the points of delivery of the elastic fluid to the vanes, the divisions forming expansion nozzles, substantially as set forth.

7. In an elastic fluid turbine, the combination with an annular set of movable vanes, of passages conducting the elastic fluid through the movable vane spaces two or more times in succession, such passages being divided at the points where the elastic fluid is delivered to and received from the vanes, such divisions forming expansion and reversed nozzles, respectively, substantially as set forth.

75 8. In an elastic fluid turbine having each of the following features, namely: an expanding delivery passage whereby the high pressure operating fluid is projected against and through the spaces between curved traveling buckets after having its energy of pressure converted into energy of motion, a converging receiving passage whereby the operating fluid after its traverse through said spaces is compressed and its energy of motion converted into energy of pressure, a stationary pocket or chamber which receives the so compressed fluid and is of greater cross sectional area than the small end of said converging passage, and an expanding delivery passage whereby the fluid from said pocket or chamber is discharged against and through another set of spaces between curved traveling buckets forming part of the same series which includes the first mentioned buckets, substantially as described.

9. An elastic fluid turbine having each of the following features, namely: a delivery passage whereby the high pressure operating fluid is projected against and through the spaces between curved traveling buckets, a converging receiving passage whereby the operating fluid after its traverse through said spaces is compressed and its energy of motion converted into energy of pressure, a stationary pocket or chamber which receives the so compressed fluid and is of greater cross sectional area than the small end of said converging passage, and an expanding delivery passage whereby the fluid from said pocket or chamber is discharged against and through another set of spaces between curved traveling buckets forming part of the same series which includes the first mentioned buckets, substantially as described.

10. An elastic fluid turbine having each of the following features, namely: a delivery passage whereby the high pressure operating fluid is projected against and through the spaces between curved traveling buckets, a plurality of converging passages whereby the operating fluid after its traverse through said spaces is compressed and its energy of motion converted into energy of pressure, and a stationary pocket or chamber which receives the so compressed fluid from said plurality of passages and an expanding delivery passage whereby the fluid from said pocket or chamber is discharged against and through another set of spaces between curved traveling buckets.

4
buckets, forming part of the same series which includes the first mentioned buckets, substantially as described.

11. An elastic fluid turbine having each of 5 the following features, namely: a delivery passage whereby the high pressure operating fluid is projected against and through the spaces between curved traveling buckets, a stationary pocket or chamber which receives 10 the said fluid after its traverse through said spaces, and a plurality of expanding delivery passages whereby the fluid from said pocket or chamber is discharged against and through another set of spaces between curved traveling buckets, forming part of the same series which includes the first mentioned buckets, substantially as described.

12. An elastic fluid turbine having each of 20 the following features, namely: a delivery passage whereby the high pressure operating fluid is projected against and through the spaces between curved traveling buckets, a plurality of converging passages whereby the operating fluid after its traverse through said 25 spaces is compressed and its energy of motion converted into energy of pressure, a stationary pocket or chamber which receives the said fluid after its traverse through said spaces, and a plurality of expanding delivery 30 passages whereby the fluid from said pocket or chamber is discharged against and through another set of spaces between curved traveling buckets forming part of the same series which includes the first mentioned buckets, 35 substantially as described.

13. In an elastic fluid turbine the combination with an annular set of movable vanes, of passages conducting the elastic fluid through the movable vane spaces two or 40 more times in succession, such passages being divided at the points of delivery of the elastic fluid to the vanes and forming nozzles, the nozzles at the first point of delivery increasing 45 in cross section in the direction of flow, and the nozzles for the second and succeeding stages being of uniform cross section beyond the throat in the direction of flow.

14. In an elastic fluid turbine of the class described, the combination with a primary 50 nozzle adapted to fully expand the compressed fluid to exhaust pressure before discharging it against the opposing vanes of the turbine wheel, of a number of consecutive

return bends of increasing size arranged alternately on each side of the turbine vanes 55 and adapted to receive the fluid and to turn it on the vanes at the proper angle to the direction of motion of the same.

15. In an elastic fluid turbine, the combination with an annular set of movable vanes, 60 of passages conducting the elastic fluid through the movable vane spaces two or more times in succession, such passages being divided at the points where the elastic fluid is delivered to and received from the vanes, 65 forming a sectional nozzle and a reversed sectional nozzle, the angle of the receiving sections being greater than that of the delivery sections, substantially as set forth.

16. In an elastic fluid turbine, the combination with an annular set of movable vanes, 70 of passages conducting the elastic fluid through the movable vane spaces two or more times in succession, such passages being divided at the points where the elastic fluid 75 is delivered to and received from the vanes, forming a sectional nozzle and a reversed sectional nozzle, the angle of the receiving sections being greater than that of the delivery sections, the angle being greater in the two or 80 more succeeding nozzles, substantially as set forth.

17. In an elastic fluid turbine, the combination with an annular set of movable vanes, 85 of passages conducting the elastic fluid through the movable vane spaces two or more times in succession, such passages being divided throughout their length, and having sectional nozzles and reversed sectional nozzles at each extremity, all of the nozzles at 90 each point of delivery and reception being of substantially the same angle of delivery.

18. In an elastic fluid turbine, the combination with an annular set of movable vanes, 95 of passages conducting the elastic fluid through the movable vane spaces two or more times in succession, such passages being divided throughout their length, and having at their extremities expansion nozzles and reversed nozzles.

This specification signed and witnessed this 23rd day of June, 1903.

CHARLES G. CURTIS.
